UNITED STATES PATENT OFFICE.

OLIVER H. REEVES, OF DENVER, COLORADO, ASSIGNOR, BY DIRECT AND MESNE ASSIGNMENTS, TO THE REEVES MOTOR COMPANY, A CORPORATION OF COLORADO.

VALVE FOR ENGINES.

1,176,402.

Specification of Letters Patent.

Patented Mar. 21, 1916.

Application filed December 16, 1913. Serial No. 807,002.

To all whom it may concern:

Be it known that I, OLIVER H. REEVES, a citizen of the United States, residing in the city and county of Denver and State of Colorado, have invented certain new and useful Improvements in Valves for Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in valves for engines, explosive engines in particular, and consists broadly in a valve composed partly of two rotative elements located one inside the other, and means for 20 moving said valve elements independently of each other.

One object of the invention is to provide an efficient substitute for the puppet valve which shall have no springs or other parts 25 likely to get out of order.

Another object of the invention is to provide a valve mechanism of this sort which shall be adapted to serve two cylinders at once, the pistons of which are working in 30 different cycles.

Still another object of the invention is to provide a single valve mechanism which shall control both the admission of fresh mixture and the expulsion of burned gases 35 for one or more cylinders.

A further object of the invention is to provide a valve in which it is practical to utilize comparatively large openings, thus tending to minimize the loss of power due 40 to back pressure.

Other objects will appear hereinafter as I proceed with the description of that embodiment of the invention, which, for the purposes of the present application, I have 45 illustrated in the accompanying drawings, in which:

Figure 1 is a central vertical longitudinal section of a portion of an internal combustion engine provided with my improved 50 valve. Fig. 2 is a vertical cross section taken upon the line 2—2, Fig. 1, looking in the direction of the arrow. Fig. 3 is a fragmental detail elevation looking in the direction of arrow 3, Fig. 2. Fig. 4 is a cross 55 sectional detail of the valve when the parts

are in the positions shown in Figs. 1, 2 and 3. Fig. 5 is a similar view illustrating the position of the valve pieces at the end of the first stroke or cycle. Fig. 6 is a similar view illustrating the positions of the valve pieces 60 at the end of the second stroke or cycle. Fig. 7 is a similar view illustrating the position of the valve pieces at the end of the third stroke or cycle.

Similar reference characters refer to like 65 parts throughout the views.

In the drawings, which form a part of this specification, let the numeral 5 refer to the crank casing of an explosive engine of two or more cylinders. In the drawings, 70 two cylinders only are illustrated as they serve to show fully the application of my new improved valve. The cylinders in the drawing are numbered 6 and 7 and are provided with a water jacket 8.

Within the cylinders 6 and 7, are pistons 9 and 10 to which are connected piston rods 12 and 13, respectively. The lower extremities of the piston rods are rotatably mounted upon crank pins 14 supported in the ends of 80 cranks 15, which in turn, are fixedly mounted in the crank shaft 16, the latter being illustrated in Fig. 1 as supported in two journals 17 and 18.

Keyed upon the shaft 16 is a gear 19 meshing with a larger gear 20. In the embodiment of my invention herein illustrated, the number of teeth in the gear 20 is twice that of the teeth in the gear 19. The gear 20 is fixed upon a shaft 21 which is rotatably 85 supported in bearings formed in lugs or ears 22, preferably made integral with the crank shaft casing or with the cylinders.

Opposite the joint, between the cylinders 6 and 7, the shaft 21 is interrupted by two 95 pairs of cranks 23 and 24, supporting crank pins 25 and 26, the cranks 23 and 24 being set apart at an angle of ninety degrees, approximately. Upon the crank pins 25 and 26 are mounted rotative bearing members 100 27 and 28, these members being each formed in two pieces secured together by bolts 29. The upper piece of each of the members 27 and 28 is bifurcated for the reception of the flattened lower extremities of connecting 105 rods 30 and 31, said extremities and bifurcations having alining perforations through which are passed bolts 32, forming pintles upon which the rods 30 and 31 may swing. At its upper extremity, the rod 31 is piv- 110

oted by the bolt 33 to a bifurcated bracket 34, swiveled to an arm 35 which is made fast by means of a set screw 36 to a shaft 37. The shaft 37 is mounted loosely in a sleeve 38 upon which is fixed, by means of a set screw 39, an arm 40, which at its opposite end carries a swiveled bracket 41, bifurcated for the reception of the flat upper end of the rod 30 to which it is pivoted by the bolt 42.

10 Cast integral with the cylinders and the water jacket 8 is a casing 43 having a cylindrical valve seat 44 therein, which is connected by means of ports 45 and 46, with the upper ends of the cylinders 6 and 7, respectively. The lower side of the valve seat opens into a chamber 47 which is connected by a short tubular casing 48 with a source of gas supply, (not shown.) On the upper side, the valve seat is in communication with

15 an exhaust port 49.

20 Formed preferably integral with the sleeve 38, is a cylindrical valve piece 50 which fits snugly within the valve seat. In the wall of the valve piece 50, are cut longitudinal slcts or ports 51, 52, 53, and 54, adapted to register respectively with the passages and ports, 49, 46, 47, and 45, of the casing.

25 Integral with the shaft 37 and arranged within the valve piece 50 is a flat substantially rectangular valve piece 55, which extends from one end of the cylindrical valve piece to the other and entirely across it dividing the interior of the cylindrical valve piece into two separate parts. Circular disks 56 are integral with the valve piece 55 and serve to close the extremities of the valve piece 50. A circular plate 57, provided with a nut shaped portion 58 for convenience in adjustment, is threaded into the casing and holds the valve pieces against longitudinal movement toward the left in Fig. 2. When the valve pieces are to be removed, the set screws 36 and 39 are loosened, 30 the plate 57 is removed, and the valve pieces are then drawn out of the valve seat toward the left in Fig. 2. The reverse operation is, of course, followed in assembling the valve.

35 From the foregoing disclosure, the operation of my improved valve mechanism may be readily understood. As the crank shaft 16 revolves in the direction of arrow A, Fig. 2, the gear 19 drives the gear 20 at half the speed of the shaft 19 in the direction of the arrow B causing the cranks 23 and 24 to be turned in the same direction. At the instant in the operation of the engine depicted in Figs. 1, 2 and 4, gas is entering the valve from the chamber 47 and passing into the cylinder 6. The continued rotation of the shafts 16 and 21 causes the rod 30 to rise rapidly, and the rod 31 to move downwardly comparatively slowly, owing to the fact that the cranks 24 are in nearly vertical positions. 40 This opposite movement of the rods 30 and

31 causes the valve pieces 50 and 55 to move in the same direction or anti-clockwise, as indicated by the small arrows in Fig. 4.

45 It will be assumed that at the beginning of the operation a charge in the cylinder 7 has just been fired, thereby forcing downwardly the piston 10 which carries with it in the same direction the piston 9, the latter by its descent drawing a charge of gas into the cylinder 6. Now, when the cranks 23 and 24 have moved through a quarter of a revolution and the valves 50 and 55 are in the position of Fig. 5, the pistons 9 and 10 have completed their descending stroke. As they rise, the piston 9, compresses the gas, 50 the port 45 having been closed by the movement of the valve pieces and simultaneously, the piston 10 expels the burned gases through the ports 46, 52 and 51, as indicated by the large arrows in Fig. 5. During this upward movement of the pistons, the rods 31 and 30 both move downwardly thereby causing the valve pieces to move in opposite directions as indicated by the small arrows in Fig. 5, until at the end of the stroke they 55 occupy the positions shown in Fig. 6.

60 At the beginning of the third stroke or cycle, the charge in the cylinder 6 is exploded, the port 45 being closed. During the stroke a new charge is drawn into the cylinder 7, as indicated by the large arrows, Fig. 6. During this stroke, the cranks 24 move upward and the cranks 23 downward, thereby causing the rotation of the valve pieces in the same direction as indicated by the 65 small arrows, Fig. 6. At the end of the third stroke when the pistons are down, the valve pieces occupy the positions of Fig. 7, the cylinder 6 beginning to exhaust through the port 45 as indicated by the large arrows 70 and the gas in cylinder 7 beginning to be compressed, the port 46 being closed. During the fourth stroke both sets of cranks 23 and 24 rise, the valve pieces moving in opposite directions as indicated by the smaller 75 arrows in Fig. 7. At the end of the fourth stroke, the cranks occupy the original positions of Fig. 2 and the valve pieces the positions of Figs. 1 and 4.

80 The direction of motion of the pistons for each stroke is indicated by the arrows C and D in Figs. 4 to 7, inclusive.

85 The form of the valve piece 55 and the arrangement and comparative size of the ports 51, 52, 53 and 54 in the valve piece 50, illustrated in the drawings, are merely 90 illustrative as it is obvious that changes in the construction of these parts and in other details described herein may be made without departing from the spirit of my invention as set forth in the appended claims.

95 I claim as my invention:

1. In an engine, a casing provided with a cylindrical valve seat and a plurality of ports in communication with said valve seat,

- a cylindrical valve piece fitting closely within said seat, a diametrically arranged valve piece fitting closely within said cylindrical valve piece, disks mounted upon the extremities of the said diametrically arranged valve piece, said cylindrical valve piece having a plurality of ports therethrough and means timed with the movements of the engine for rotating said valve pieces upon a common axis independently of each other. 10
2. In an engine, a casing provided with a cylindrical valve seat and plurality of ports communicating with said valve seat, a cylindrical valve piece closed at its ends fitting closely within said valve seat, a valve piece mounted within and dividing the interior of said cylindrical valve piece into two parts, said cylindrical valve piece having a plurality of ports therethrough adapted to register with the ports in said casing and means timed with the movements of the engine for rotating both of said valve pieces independently of each other upon the axis of the cylindrical valve piece. 15
- 20 3. In an explosive engine, an engine cylinder, a gas supply source, an exhaust port, a casing provided with a cylindrical valve seat, said casing having therein a port connecting the engine cylinder and valve seat, a passage connecting the seat with the exhaust port and a passage connecting the seat with the source of gas supply, a cylindrical valve piece fitting closely within said valve seat, a diametrically arranged substantially rectangular valve piece mounted within and dividing the interior of said cylindrical valve piece into two parts, circular disks upon the ends of said rectangular valve piece arranged to close the ends of the cylindrical valve piece, said cylindrical valve piece having a plurality of ports therethrough, adapted to register with the port and passages in said casing and means for rocking both of said valve pieces independently of each other upon the axis of the cylindrical valve piece in synchronism with the movements of the engine. 25
- 40 4. In an explosive engine, an engine cylinder, a gas supply source, an exhaust port, a casing provided with a cylindrical valve seat, said casing having therein a port connecting the engine cylinder and valve seat, a passage connecting the seat with the exhaust port and a passage connecting the seat with the source of gas supply, a cylindrical valve piece fitting closely within said valve seat, a diametrically arranged substantially rectangular valve piece mounted within and dividing the interior of said cylindrical valve piece into two parts, circular disks upon the ends of said rectangular valve piece arranged to close the ends of the cylindrical valve piece into two parts, circular disks upon the ends of said rectangular valve piece arranged to close the ends of the
5. In a four cycle explosive engine, an engine cylinder and piston, a gas supply source, an exhaust port, a casing provided with a cylindrical valve seat, said casing having therein a port connecting the engine cylinder, and valve seat, a passage connecting the seat with the exhaust port and a passage connecting the gas supply source with the seat, a cylindrical valve piece closed at its ends, fitting closely within said valve seat and having ports adapted to register with the port and passages of the casing, a diametrically arranged substantially rectangular valve piece mounted within and fitting closely, said cylindrical valve piece and means for rocking both of said valve pieces upon the axis of the circular valve piece for opening communication between the cylinder and gas supply during one cycle of the piston, closing the cylinder during the next two cycles, and opening communication between the cylinder and exhaust port during the fourth cycle. 50
6. In a multi cylinder engine, provided with a gas supply and an exhaust port, a casing between each pair of cylinders having therein a cylindrical valve seat, said casing having ports connecting said cylinders with the valve seat and passages connecting the valve seat with the gas supply and exhaust port, a cylindrical valve piece fitting closely within said seat, a valve piece fitting closely within said cylindrical valve piece and arranged to divide the interior thereof into two parts, said cylindrical valve piece having a plurality of ports therethrough and means timed with the movements of the engine for rocking said valve pieces upon a common axis independently of each other. 55
7. In an engine, a valve comprising a cylindrical member closed at its ends, and a diametrically arranged member fitting snugly into the cylindrical member, the cylindrical member being provided with a plurality of ports, and means for actuating said members independently of each other. 60

In testimony whereof I affix my signature in presence of two witnesses.

OLIVER H. REEVES.
